UNITED STATES PATENT OFFICE.

WILLIAM S. MILLER, OF PROVIDENCE, RHODE ISLAND, ASSIGNOR TO ARTHUR W. PUSEY, OF FERNWOOD, PENNSYLVANIA.

LOAD-COMPENSATOR.

1,300,755.

Specification of Letters Patent. Patented Apr. 15, 1919.

Application filed May 17, 1916, Serial No. 98,004. Renewed February 25, 1919. Serial No. 279,222.

To all whom it may concern:

Be it known that I, WILLIAM S. MILLER, a citizen of the United States, residing in the city and county of Providence, State of 5 Rhode Island, have invented a new and useful Load-Compensator, of which the following is a specification.

My present invention consists of a novel construction of a load compensator which 10 can be employed in conjunction with any desired type of vehicle and which is especially applicable to motor driven vehicles.

It further consists of a novel load compensator which includes a cushioning element and a spring element with a connection between them constructed and arranged in such a manner that the parts coöperate to provide substantially the same resiliency irrespective of the load to which the vehicle 20 is subjected.

It further consists of a novel construction of a load compensator in which the ratio of flexibility of the spring suspension for the vehicle body is substantially the same under 25 any load and wherein under maximum load the shock absorber has practically the full capacity to work against shocks and road inequalities.

It further consists of a novel construction 30 of load compensator which may be used in conjunction with any type of vehicles by simply changing the type of lever employed and wherein the effective length of the lever arm which coöperates with the vehicle spring 35 is automatically varied in accordance with the variation of load on the vehicle.

It further consists of a novel device of the character stated, wherein the side sway of the vehicle body is prevented and wherein 40 in the eye of the spring is held to its line of travel in a guide box carried by the vehicle spring or an extension therefrom.

Other novel features of advantage and construction will hereinafter more clearly 45 appear in the detailed description.

For the purpose of illustrating my invention, I have shown in the accompanying drawings one form thereof which is at present preferred by me, since the same will 50 give in practice satisfactory and reliable results, although it is to be understood that the various instrumentalities of which my

invention consists can be variously arranged and organized and that my invention is not limited to the precise arrangement and organization of these instrumentalities as herein shown and described.

Figure 1 represents a side elevation, partly broken away, of a vehicle frame in conjunction with which a load compensator 60 embodying my invention is employed.

Fig. 2 represents a sectional elevation showing certain of the parts seen in Fig. 1 in a different relation from that seen in said figure.

Fig. 3 represents a section on line 3—3 of Fig. 1.

Fig. 4 represents a sectional elevation similar to that seen in Fig. 2, but showing the parts in the position they assume at a predetermined increase in load on the vehicle.

Similar numerals of reference indicate corresponding parts in the figures.

Referring to the drawings:—

1 designates the frame or an extension thereof of a vehicle body which latter may be of any desired type. My invention, however, is especially adapted to be employed in conjunction with vehicles which are motor driven. 2 designates a bracket which is fixed to the frame 1 by means of fastening devices 3 of any desired type. The bracket 2 is provided with a table 4 which supports a spring 5 which is normally concealed 80 within the telescoping sections 6 and 7 of the shock absorbing or cushioning member 8.

9 designates a spring abutment comprising a plate engaging the upper end of the spring 5 and to this plate is connected in any desired manner a rod 10, the lower end of which is connected to one end of a link 11, the other end of said link being pivoted to one end of a lever 12 which is provided with trunnions 13 which are journaled in hubs 14 of the guide box formed by the depending standards 15, the latter being formed by bifurcating the lower end of the bracket 2. In order to stiffen the standards 15, their lower ends are connected by means 95 of a fastening device 16.

17 designates a spring which may be of any desired or conventional type and which is provided with any desired number of

leaves, the outer one of which, in the present instance, is deflected upon itself to form an eye 18 through which passes a rod 19, the ends of which are fixed in any desired manner to a bearing box 20, which is provided with a laterally extending bottom 21 and the upwardly projecting sides 22 to which latter the ends of the rod 19 are secured. The eye carrying leaf of the spring 17 has 10 a bearing on the upper face of the bottom 21 and is retained in position and prevented from rattling by means of a cross member 23 secured to the sides 22 of the bearing box.

24 designates an anti-friction device of 15 any desired type, such as a roll or other anti-friction bearing, and which is illustrated as consisting of a rod having its ends fixed in the side members 22 of the bearing box a desired distance below the upper 20 end thereof. The lever arm 25 is adapted to have its under face 26 rest upon the anti-friction roll 24, and the lever arm 25 is guided between the standards 15 of the bracket 2, as will be understood by reference 25 to Figs. 2, 3 and 4.

It will be understood that upon a predetermined increase in the load, the point of contact of the roller 24 with the lever connected with the shock absorbing element 30 will automatically vary in accordance with variations in load.

The spring 17 is connected with the bearing box 20 in any desired manner, so as to prevent relative movement of such bearing 35 box and the spring 17.

It will, of course, be apparent that the type of lever employed will vary in accordance with the conditions and requirements met with in practice. Under any load the 40 ratio of flexibility is the same and the capacity of the shock absorbing element is present to occasion and absorb the shocks to which the vehicle is subjected.

Under maximum load, the device has practically 45 its full capacity to work against the shocks and road inequalities.

The deflection of the frame or floor of the vehicle is no greater than with ordinary 50 spring suspension. By varying the capacity of the springs, the flexibility can be correspondingly varied, as is apparent.

It will further be apparent that the ratio of the load to the capacity of the shock absorbing elements is always the same.

55 It will also be apparent that in accordance with my present invention, I may employ any type of shock absorber or cushion, and any desired type of compression, tension, or other type of springs may be employed to effect the cushioning action.

It will be seen that any side sway of the springs is prevented, owing to the manner in which they are carried by and guided in the bearing box.

65 In the embodiment shown, I employ a

lever whose point of fulcrum is fixed, said lever being operatively connected with the shock absorbing element and said lever being connected with the spring in such a manner that the effective length of the lever arm 70 automatically varies in accordance with the variation in load which the vehicle carries.

It will, of course, be understood that my present device can be employed in conjunction with any or all of the ordinary springs 75 of a vehicle without departing from the spirit and scope of the invention.

It will now be apparent that I have devised a novel and useful load compensator, which embodies the features of advantage 80 enumerated as desirable in the statement of the invention and the above description, and while I have, in the present instance, shown and described a preferred embodiment thereof of which will give in practice satisfactory 85 and reliable results, it is to be understood that the same is susceptible of modification in various particulars without departing from the spirit or scope of the invention or sacrificing any of its advantages. 90

Having thus described my invention, what I claim as new and desire to secure by Letters Patent, is:—

1. In a load compensator, a vehicle frame, a bracket carried thereby, a shock absorbing element, a lever fulcrumed in said bracket and having one end operatively connected with said shock absorbing element, a supporting spring, and a bearing member carried by the supporting springs, guided by 100 said bracket, and in sliding engagement with the other end of said lever. 95

2. In a load compensator, a vehicle frame, a shock absorbing element carried by it, a supporting spring, a bearing box secured to 105 said spring, and a fulcrumed lever carried by said frame and having one end operatively connected with said shock absorbing element and its other end having a sliding connection with the bearing box. 110

3. In a load compensator, a vehicle frame, a shock absorbing element carried by it, a supporting spring, a lever carried by said frame and having one end operatively connected with said shock absorbing element, a bearing box having a bottom in bearing engagement with the spring and having sides, and a bearing member carried by said sides and in sliding engagement with the other end of said lever. 115

4. In a load compensator, a vehicle frame, a bracket carried by it, a compression spring supported on said bracket, an abutment for the upper end of said spring, a lever pivotally carried by said vehicle frame and having one end operatively connected with said abutment, a supporting spring, and means carried by said supporting spring on which the other end of said lever has a sliding bearing. 125

5. In a load compensator, a vehicle frame, a shock absorbing element carried by said frame, a lever pivotally carried by said frame and having one end operatively connected with an antifriction bearing on which the other end of said lever is free to slide.

a shock absorbing element carried by said frame, a lever pivotally carried by said frame and having one end operatively connected with an antifriction bearing on which the other end of said lever is free to slide.

WILLIAM S. MILLER.
